U.S. Appl. No. 29/426,408, Applicant: Ok-Keun Lee, et al., filed Jul. 5, 2012 entitled TV Receiver.

* cited by examiner

Primary Examiner — Randall Gholson

(74) *Attorney, Agent, or Firm* — Flynn, Thiel, Boutell & Tanis, P.C.

(57) **CLAIM**

The ornamental design for a TV receiver, as shown and described.

DESCRIPTION

FIG. 1 is a top front perspective view of a TV receiver showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detail view of the bottom of the TV receiver as shown in FIG. 3;

FIG. 9 is a fragmentary and enlarged cross-sectional view as seen generally along line 9-9 in FIG. 8; and,

FIG. 10 is a rear perspective view thereof.

The broken lines depict environmental subject matter only and form no part of the claimed design.
